UNITED STATES PATENT OFFICE.

HORACE GARST, OF COUNCIL BLUFFS, IOWA.

HEAD-SCREEN

SPECIFICATION forming part of Letters Patent No. 336,712, dated February 23, 1886.

Application filed September 11, 1885. Serial No. 176,799. (No model.)

To all whom it may concern:

Be it known that I, HORACE GARST, of Council Bluffs, in the county of Pottawattamie and State of Iowa, have invented certain new and useful Improvements in Head-Screens, of which the following is a full, clear, and exact description.

Reference is to be had to the accompanying drawings, forming part of this specification, in which similar letters of reference indicate corresponding parts in all the figures.

Figure 1 is an elevation of one of my improved screens, illustrating its use. Fig. 2 is an elevation of the same detached. Fig. 3 is a view showing the forward part of the screen raised. Fig. 4 is a view showing the whole of the screen raised and arranged upon the hat.

The object of this invention is to provide screens for protecting the heads of the wearers from mosquitos, flies, and other insects, and from dust, and which shall be so constructed as to be worn over an ordinary hat without inconvenience.

The invention consists in a head-screen constructed with an elastic or non-elastic band at its upper edge, an elastic or non-elastic band at a little distance from its lower edge, and with a flexible series of weights along its lower edge, as will be hereinafter fully described and claimed.

The body A of the screen is made of mosquito-netting or fine gauze, and is in the shape of a bag, open at bottom and open or closed at top. The body A is made of a greater diameter than the hat upon which it is to be worn, and at its upper edge is formed a hem, in which is run an elastic or non-elastic band or cord, B, of such a size or so adjusted as to fit upon any desired part of the hat-body, and of such an elasticity or so adjusted as to retain its position upon the part of the hat-body upon which it may be placed. Around the body A, at a little distance from its lower end, is formed a shirr, in which is inserted an elastic or non-elastic band, C, which is designed to confine the said body A loosely around the neck of the wearer. At the lower edge of the body A is formed a hem, in which is inserted a flexible series of weights, D. The series of weights can be formed by securing shot in a tubular fabric, and then preventing the said shot from having any movement along the said tube by

cross-stitches or other suitable means. With this construction the weighted lower edge of the screen will rest and fit closely to the shoulders, breast, and back of the wearer, its flexibility allowing it to adjust itself to all inequalities in the clothing, so that mosquitos and flies will be prevented from passing up beneath the said lower edge of the screen, and the said weights will be supported by the shoulders of the wearer. With this construction the lower part of the screen will adjust itself automatically to rest upon the neck and shoulders of the wearer in such a manner as to leave the head and hat free from any pressure from the weight of the lower part of the screen. With this construction, also, the wearer can raise any part of the screen—as, for instance, in front—as illustrated in Fig. 3, to allow him to eat, drink, or smoke, by raising the forward part of the flexible series of weights D and laying them upon the hat-brim, the band or cord C resting against the forehead of the wearer, all the other parts of the head and neck, except the desired exposed part, being fully protected. When the raised part of the series of weights D is removed from the hat-brim and allowed to drop, the lower part of the screen will again adjust itself in place automatically. With this construction, also, the entire screen can be raised above the hat-rim and worn around the hat, as illustrated in Fig. 4.

I am aware that a mosquito-guard has been composed of a frame-work covered with netting and adapted to be drawn close around the neck of the wearer; and I do not claim such as of my invention.

Having thus described my invention, I claim as new and desire to secure by Letters Patent—

A head-screen, A, made substantially as herein shown and described, with a band, B, at its upper end, to fit upon a hat-body, an elastic or non-elastic band, C, in its lower part, to fit loosely around the neck of the wearer, and with a flexible series of weights, D, at its lower edge, to rest upon the shoulders, breast, and back of the wearer and be supported by the said shoulders, as set forth.

HORACE GARST.
